UNITED STATES PATENT OFFICE.

CLARENCE F. TRUE, OF NEW YORK, N. Y.

PORTRABLE KITCHEN.

1,176,106.

Specification of Letters Patent. Patented Mar. 21, 1916.

Application filed September 7, 1912. Serial No. 719,072.

To all whom it may concern:

Be it known that I, CLARENCE F. TRUE, a citizen of the United States, and a resident of borough of Manhattan, in the county 5 of New York, city and State of New York, have invented certain new and useful Improvements in Portable Kitchens, of which the following is a specification.

The invention relates to vehicles designed 10 for the purpose of conveying, storing and preparing food, such as commissary wagons used by armies in the field, and its objects are, among others, to provide a device of this character of simple, strong and durable 15 construction which may be used for cooking, conveying and refrigerating food, provided with parts which may be converted into tables when the food is to be served, and to so construct and arrange the various parts of 20 the device that they will coöperate and co-ordinate with one another to bring about a maximum of convenience and efficiency, together with the greatest compactness and portableness.

25 The invention consists of the construction, combination and arrangement of parts hereinafter described and claimed and illustrated in the accompanying drawings.

In the said drawings, Figure 1 is a longitudinal vertical section of an army field 30 kitchen embodying the improvements; Fig. 2 is a horizontal section taken on the line 2—2 of Fig. 1 looking in the directions indicated by the arrows.

35 The wagon forming a part of the field kitchen consists of a body A mounted by means of suitable spring trucks B B' C C'. Upon this body is mounted a hood-frame composed of longitudinal strips D and D⁵, 40 cross-strips D' and D², the latter formed of the same strips of which the uprights D³ supporting the hood are formed. The hood frame extends over the driver's seat at the front of the wagon and is provided with 45 a waterproof cover D⁴ of canvas or other suitable material.

At the rear the hood is provided with an extension consisting of the rectangular frame E, hinged to the hood-frame at E' and a 50 flexible cover E² supported thereby and depending at the extreme rear. This extension may be lowered by breaking the elbow 100

joint E⁴ of the brace rod E³, which normally holds it in its upper and extended position, and when this is done the cover E² may be 55 rolled up. The sides of the main hood cover may also be rolled up as shown at D⁶.

The hood is provided with an annulus F² having a depending collar F³ and supported by a bracket F⁴ fixed to the hood frame, for 60 the purpose of receiving and supporting the chimney F of the cooking stove G. A collar F⁵ secured to the hood frame supports is also provided at about mid-height of the chimney.

The range G may be of any suitable construction, and is provided with a water heater H at the back of the fire pot and communicating with the hot water tank H' at the rear. Above this hot water tank are 70 mounted fireless cookers J composed of casings provided with non-heat conducting walls J' and a hinged door J². Within these casings are metallic food receptacles J³ mounted on casters J⁴.

At the forward part of the wagon is located a refrigerator I, and between the said refrigerator and the fireless cookers is a space which may be used for the storage and transportation of various articles. Beneath the driver's foot rest K is a compartment K', provided with a hinged door K² which may also be used for the storage of supplies.

The side-boards L of the wagon are removable and are provided with strips L' bearing sockets L² adapted to receive the legs L³ shown stored in the compartment M beneath the wagon body. In this manner the boards may be removed and used for a 85 table. Tables N are also carried by the cookers and the refrigerator, the table top in each instance forming a cover for the said device and being held in position by the depending portions N'. The legs N² of these 90 tables are hinged and are adapted to be folded between the table-top and the top of the refrigerator or cooker as the case may be, and in this position the rectangular leg tops N³ provide a firm base. These tables 95 tops N³ not only protect the said devices from the weather and the influence of the atmosphere, but provide seats for those detailed to the care of the kitchen.

The door J^2 opens outwardly and upwardly, and permits the metallic food receptacle J^3 to slide in and out, the casters J^4 facilitating this movement of the said receptacles. It is, therefore, only necessary to open the door J^2 and draw the receptacle out upon the top of the range when food is to be cooked or heated therein, and to roll it back within the casing of the fireless cooker after it has been used for this purpose.

The side curtains of the wagon are made of unusual length, preferably so as to extend to the ground, when allowed to drop, and these curtains are provided with ropes D^7 at their lower edges so that they may be drawn out and secured by having the ropes staked or otherwise fastened, so as to form a tent-like structure over the tables on the ground at the sides of the wagon as well as to protect the wagon and its contents.

Other details of construction are the channel iron sills of the wagon A^1 , the steps A^2 , the hasp K^3 of the door K^2 and the pipe H^2 provided with a faucet H^3 through which hot water may be drawn from the hot water tank. It will be understood that each receptacle is provided with a door or other suitable opening, where the same is required.

30 What I claim is:

1. In a device of the character described, the combination with a wagon body and wheels upon which the same is mounted to travel, of compartments mounted thereon and adapted to receive and hold food and provisions, one of said compartments being provided with a removable receptacle and non-heat conducting walls, a heating device mounted exterior to the wagon body in proximity to said compartment and the said compartment having a door through which the removable receptacle may be passed to the said heating device adjacent thereto.

2. In a device of the character described, the combination with a wagon body and wheels upon which the same is mounted to travel, of compartments for food and provisions carried thereby, tables constructed and arranged to be mounted on said compartments for use, said compartments being spaced apart to permit the person using the tables to stand between them, and said tables being provided with extensible means whereby when removed from the compartments they may be supported upon the ground.

3. In a device of the character described, the combination with a wagon body and wheels upon which the same is mounted to travel, of a cooking device mounted exterior thereto, and a compartment adjacent to said cooking device having non-heat conducting walls, the said compartment having a door adjacent to the cooking device and a container therein adapted to pass through

said door on to the said cooking device, the upper surface of the cooking device and the bottom of the compartment being substantially in plane.

4. In a device of the character described, the combination with a wagon body and wheels upon which the same is mounted to travel, of compartments for food and provisions mounted thereon, table tops mounted on said compartments so as to provide tables within the vehicle, side-boards on said body, a space within the body being provided between said compartments and side-boards and inclosed thereby for a person using the tables, said tables and side-boards being removable and provided with means whereby when removed they may be supported on the ground.

5. The combination of rolling supports, a wagon frame mounted thereon, storage and cooking compartments mounted in said frame, the latter having non-heat conducting walls, and spaces between said compartments providing room for persons to stand therein, and the tops of said compartments being approximately at a normal table level, so that they can be utilized for the preparation of food and other purposes of a table.

6. The combination of rolling supports, a wagon frame mounted thereon, storage and cooking compartments mounted in said frame, the latter having non-heat conducting walls, the tops of said compartments being approximately at a normal table level, so that they can be utilized for the preparation of food and other purposes of a table, said tops being removably mounted on said compartments, and adjustable supports for said tops, whereby after removal from the compartments they may be supported in an elevated position.

7. The combination of a wagon bottom, axles upon which the same is mounted, and wheels journaled on the said axles, compartments mounted on said wagon bottom adapted to contain food and provisions, one of said compartments having non-heat conducting walls, a heating device supported below said bottom and exterior thereto, said last named compartment having an opening provided with a door adjacent to the upper part of the heating device, a receptacle adapted to be placed within said compartment and inclosed therein, the construction and arrangement being such that the said receptacle may be moved from the bottom of said compartment to the top of the heating device and in the opposite manner while being supported by one or both of said parts.

8. The combination of a wagon bottom, axles upon which the same is mounted, and wheels journaled on the said axles, compartments mounted on said wagon bottom adapted to contain food and provisions, a heating device supported below said bottom and ex-

terior thereto, and a water compartment adjacent to the said heating device and constructed and arranged to have its contents heated thereby, said water compartment supported below the wagon bottom and having an outlet below the heating device.

Witness my hand this 3rd day of September,

1912, at the city of New York, in the county and State of New York.

CLARENCE F. TRUE.
